In Belgium May 11, 1933

2 Claims. (Cl. 62—119)

This invention relates to refrigerating apparatus of the general type in which the refrigerant, for instance ammonia, in various states of aggregation performs a cycle through a boiler and a gas expeller, a condenser, an evaporator and an absorber.

In known apparatus of this kind the liquor in the boiler has a relatively large surface, whereas as the pipe, through which the weak liquor flows by gravity to the absorber, is in direct communication with the vapour space of the boiler. The first said feature has the advantage that the vapours flowing to the condenser are fairly dry, but in view of the said direct communication of the overflow pipe with the vapour space of the gas expeller it has the inconvenience that during the ebullition the level of the liquor in the boiler is raised only through a small height, so that the static pressure for maintaining the circulation of liquid between boiler and absorber is hardly sufficient.

It has been suggested to avoid the said inconvenience by submitting the liquor from the boiler to a further heating action in a narrow ascending pipe opening into the vapour space of the gas expeller. This construction, while allowing liquor to be lifted to a higher level and thus ensuring a rapid circulation of liquid through the other elements of the apparatus by differences of level, has the serious draw-back that the very wet vapours produced by the violent boiling liquid in the ascending pipe reach the condenser. Moreover, the relatively high temperature required for further degasification of the liquor in the ascending pipe may, in the long run, unfavourably affect the composition of the refrigerant.

In order to obviate said drawback, it has been suggested to connect the ascending pipe with the absorber in such a manner that no vapours from said pipe can flow into the condenser.

My present invention has for its object to still further improve refrigerating apparatus of last said type, and more particularly to ensure a still higher lift of the liquor level in the ascending pipe. With this object in view, the lower end of the ascending pipe opens into a reservoir adapted to be heated and communicating with, and preferably placed inside the boiler, whereas a conduit is provided through which part of the liquor returning from the absorber to the boiler can be by-passed to said reservoir. It will be understood that the word "reservoir" here is to be construed in its widest sense, and that it is intended to also include, for instance, a simple flare or funnel.

In my novel construction, the liquid in the reservoir will have substantially the same temperature as that in the gas expeller, but as its concentration, owing to the direct inflow of rich liquor from the absorber, is much higher, a violent ebullition will take place therein, so that the liquor in the ascending pipe can be lifted to an exceptionally high level. Nevertheless, it is impossible for wet vapours to reach the condenser, since the ascending pipe does not open into the vapour space of the boiler. 5

Preferably, a separating chamber will be interposed, in a manner known per se, in the conduit between the ascending pipe and the absorber, in order to separate the (wet) refrigerant vapours from the absorption liquid. In that case the vapour space of said chamber may, in accordance with the invention, be connected with the liquor return pipe before the point of entry of the aforesaid bye-pass. Thereby, the concentration of the bye-passed liquor and, consequently, that of the liquor in the reservoir is still further increased.

The annexed diagrammatic drawing illustrates, by way of example only, a refrigerating apparatus in accordance with the invention.

In this drawing, 1 is the boiler, 2 a tube fitted within the boiler and adapted to be heated, for instance, by an electric heating element not shown. Near its top, the boiler 1 is connected through a tube 3 with the condenser 4, which in turn communicates with the evaporator 6 by means of a pipe 5. The evaporator 6 is connected by a tube 7 with the absorber 8, the lower portion of which is in direct communication with the upper portion of the boiler 1 through a conduit 9.

Partly enclosing the inner tube 2 is arranged a bell-shaped, i. e. open-bottom, thin walled metallic reservoir 10 provided with an ascending pipe 11. This pipe opens into a chamber 12 near the top thereof, a pipe 13 connecting the bottom of said chamber with the upper portion of the absorber 8. As shown, pipe 13 is, through part of its length, enclosed by the return pipe 45 9 so as to form a heat exchanger therewith. Near its top the chamber 12 communicates with the return pipe 9 by means of a vapour discharge pipe 14. Intermediate the exit of pipe 14 and the boiler 1, the return pipe 9 is connected with the lower portion of reservoir 10 through a bye-pass 15 fitted with a valve 16.

The aqueous solution of ammonia contained in the boiler 1 is heated to the required temperature. The ammonia vapours expelled thereby 55

flow through pipe 3 to the condenser 4, where they are liquefied. From the condenser, the liquid ammonia flows into the evaporator 6, where it is again vaporized to produce cold, the vapour being discharged into the absorber 8.

In the absorber 8, the water is at substantially the same level as in the boiler 1. Near the top of the absorber, water is introduced through pipe 13. It is to be understood that, owing to the generation of the vapour bubbles in the liquor contained in boiler 1, said liquor will ascend in pipe 11 so as to reach the separator 12, in which the water collects near the bottom and the ammonia vapour collects in the upper part. The water is discharged through pipe 13 and supplied, by its own static pressure, to absorber 8, where as the vapour is fed, by pipe 14, into the conduit 9 through which the rich liquor from the absorber 8 is returned to the boiler 1. Said rich liquor is thus still further concentrated, and part thereof is bye-passed through pipe 15 to flow directly into the reservoir 10. As this reservoir is directly heated by the tube 2, a relatively great amount of ammonia vapour is generated therein,

so that the separator 12 may be placed at a considerably higher level than the boiler 1 and the absorber 8 and a strong liquid circulation brought about.

What I claim is:—

1. In an absorption refrigerating apparatus of the type wherein the refrigerant, in various states of aggregation, performs a cycle through a boiler or gas expeller, a condenser, an evaporator and an absorber, a boiler provided with a separate ascending pipe, a vapour separator connected with said pipe, a second pipe connecting said separator with the absorber, the lower end of said ascending pipe opening into a reservoir adapted to be heated and communicating with the boiler and a conduit through which part of the liquor returning from absorber to boiler can be bye-passed to said reservoir.

2. Absorption refrigerating apparatus in accordance with claim 1, in which the vapour space of said separator is connected with the liquor return pipe at a point before the entry of the said bye-pass.

ALEXANDER BIKKERS.
